UNITED STATES PATENT OFFICE.

ABRAHAM L. YOUNG, OF PARIS, ILLINOIS.

DUMPING APPARATUS FOR VEHICLES.

SPECIFICATION forming part of Letters Patent No. 783,165, dated February 21, 1905.

Application filed June 4, 1904. Serial No. 211,102.

To all whom it may concern:

Be it known that I, ABRAHAM L. YOUNG, a citizen of the United States, residing at Paris, in the county of Edgar and State of Illinois, have invented a new and useful Improvement 5 in Dumping Apparatus for Vehicles, of which the following is a specification.

My invention relates to means for transporting and quickly delivering a great variety 10 of loose materials, and is adapted to service in railway as well as common road cars and wagons, my object being to provide a construction giving a high efficiency at a moderate cost, the same being fully described hereinaf- 15 ter and is fully illustrated in the accompanying drawings, in which—

Figure 1 is a bottom plan of a common wagon-box bed, showing some of the principal parts of my dumping attachment. Fig. 20 2 is a transverse section on broken line A B, Figs. 1 and 5, to illustrate the position of the operative parts when in the closed state. Fig. 3 is the same section as Fig. 2 with the parts in the open position. Fig. 4 is a bottom plan 25 of one of the dumper-shutters to more clearly illustrate the construction. Fig. 5 is a side elevation of the wagon-bed to illustrate means for operating the dumping-shutters. Fig. 6 is a plan of the wagon-bed to illustrate several 30 principal operative features not shown in Fig. 1, such as the top appearance of the dumping-shutters and other parts which form the bottom of the bed. Fig. 7 is an elevation of the 35 front end of the bed, showing levers for operating the dumping-shutters. Fig. 8 is a cross-section on broken line E F, Figs. 1 and 6, which is close to the front bolster, to show 40 position of the side slots in the dumper-shutters to permit the latter to fall to the open position astraddle the bolsters as in Fig. 3.

Similar numerals indicate like parts throughout the several views.

The drawings show the common road-wagon-bed form of this dumping apparatus, in which 45 1 and 2 are bolsters and 3 and 4 the vertical sides of the bed, in each of which latter is a series of grooves 5, which are wide and vertically disposed. In each side also is a longitudinal groove crossing the grooves 5, and 50 in each longitudinal groove is mounted in

bearings a long shaft 7, which is bent into a series of double cranks 8, which occupy the wide vertical grooves 5, the cranks being adapted to assume by turning the handle-arms 9 at the front end of the bed, Figs. 5, 6, and 55 9, either the upper or lower positions, as shown in Figs. 2 and 3, the handles being held in the lower position locked by being sprung under pins 9'. Each of these cranks has loosely attached thereto the upper end of a 60 vertically-disposed connecting-rod 10, the lower end being loosely in engagement with the outer end of a clip 11, projecting from the outer sides of the dumping-shutters 12 and 13. The length of each rod is such that when the 65 cranks 8 are in a raised position the shutters will be closed, with the rods each extending substantially across the axis of the crank-rod, thereby forming dead-centers and automatically locking the shutters in their closed position. Longitudinally disposed there is secured at the ends of the bed, at the center of width, the ends of a strip 14, which has a triangular cross-section, Figs. 2, 3, and 8, the strip being so disposed that one of the points or angles is at the top to prevent lodgment of material being dumped. The dumping-shutters are each pivotally attached at the bottom ends 70 of the bed at 15 at about one-third the distance of the triangular strip from the inner 75 faces of the sides of the bed. There are long strips 19 and 20 secured to the inside surface of the bed, which serve to close the outside margins of the dumper-shutters. There is a close-fitting strip of elastic or pliable material 80 21 secured to the ends of the dumping-shutters to prevent leakage of fine materials, yet not prevent the easy movement in opening or closing the shutters. The dumping-shutters are each slotted about two-thirds across their 85 width from the outside, or to a point substantially in line with the pivotal points at 15, as plainly indicated in Fig. 4, to straddle the bolsters when being turned to the position shown in Fig. 3, and these slots may be bordered with flexible strips similar to end strips 21, but secured to the bottom faces of the shutters against the bolster side faces to prevent leakage in the slots.

In operation the dumper-shutters 12 and 100

13 being closed, as shown in Figs. 1, 2, 6, and 8, and the bed filled with loose material the latter may be dumped by disengaging the levers 9 and pressing them forwardly from engagement with pins 9', when by virtue of the upward and outward movement of the levers and the weight of the materials in the bed the dumping-shutters are made to assume the position shown in Fig. 3 and the material 5 permitted to pass downwardly, as indicated by the arrows in Fig. 3. By reversing the movement of levers 9 it is obvious that the dumping-shutters will be turned to the nearly-closed position when the levers 9 are sprung 10 forwardly and downwardly, and then they spring inwardly in engagement with pins 9', and in the locked position shown in Fig. 7 when the shutters are fully closed.

It will be noticed that when the levers 6 are 20 in the locked position the cranks 8 of shaft 7 are all at or past the upper center, so that there is no tendency to turn outwardly and dump a load, since very little strain is imposed to twist the shaft or disengage levers 9 25 from the pins 9'.

I claim as my invention—

1. In a dumping apparatus for vehicles, a receptacle for materials to be dumped having a bottom consisting in part of shutters each pivotally connected to the receptacle at the ends aside of the center of width of the shutters and notched from the outer edge to a point substantially in a line with the pivotal points at the ends, and means connected with the shutters through which their position relative to the receptacle is controlled.

2. In a dumping apparatus for vehicles, a receptacle for materials to be dumped having a bottom consisting of two shutters each pivotally connected to the receptacle at the ends aside of the center of width of the shutters, and means through which their relative position is controlled consisting of revoluble shafts mounted at the sides of the receptacle, 40 and which are bent to form double cranks, connecting-rods between the cranks and the shut- 45

ters, and hand-levers connected with the shafts, for the purpose as shown and described.

3. In a dumping apparatus for vehicles, a receptacle for materials to be dumped having a bottom comprising two shutters each pivotally connected to the receptacle at the ends aside of the center of width of the shutters, a central support secured to the receptacle at the ends and between the shutters in close proximity to the latter in the closed position, strips secured to the inside surface of the receptacle in position to overlap the edges of the shutters when in their closed position, and means connected with the shutters for controlling and for holding the shutters in the closed position, substantially as described.

4. In a dumping apparatus for vehicles, a receptacle for materials to be dumped having each side recessed longitudinally and transversely, two pivoted shutters for the bottom of the receptacle, a double-crank rod mounted in each longitudinal recess in the sides, the cranks of which fit in the transverse recesses, means for rotating said rods, and means for connecting the cranks with the outer edges of the shutters.

5. In a dumping apparatus for vehicles, a receptacle for materials to be dumped having a bottom comprising two pivoted shutters, a double-crank rod mounted on each side of the receptacle, the forward end of which is provided with a handle, a stop for each handle, and rods for connecting the cranks with the outer edges of the shutters, said rods being of such a length that when the cranks are in a raised position, each rod will extend substantially across the axis of the crank-rod and automatically lock the shutters in a closed position.

In witness whereof I have hereunto set my hand, this 28th day of May, 1904, in the presence of two subscribing witnesses.

ABRAHAM L. YOUNG.
